Oran Geier

UNITED STATES PATENT OFFICE.

STEPHEN WINTER, OF BRIDGEPORT, CONNECTICUT.

SKEE OR SNOW-SHOE.

1,317,770.

Specification of Letters Patent. Patented Oct. 7, 1919.

Application filed November 16, 1918. Serial No. 262,754.

To all whom it may concern:

Be it known that I, STEPHEN WINTER, a subject of the King of Hungary, residing at Bridgeport, county of Fairfield, and State 5 of Connecticut, have invented certain new and useful Improvements in Skees or Snow-Shoes, of which the following is a specification.

This invention relates to improvements 10 in skees or snow shoes such as are used in traveling on the surface of snow.

The principal object of the invention is to provide means whereby the feet of the operator are so engaged with the snow shoe 15 as to allow a limited amount of movement thereon permitting the operator to move the lower limbs and feet in a natural manner as in walking.

A further object is to provide means 20 whereby the runners of the skee may be folded, thus allowing the same to be readily carried, or packed in a small parcel when not in actual use.

A still further object is to provide means 25 whereby the runners, when extended or folded, may be firmly locked in position.

These and other like objects are attained 30 by the novel construction and combination of parts hereinafter described and shown in the accompanying drawings, forming a material part of this disclosure, and in which—

Figure 1 is a side elevational view showing 35 a skee runner made in accordance with the invention, and indicating its application.

Fig. 2 is a sectional view taken on line 2—2 of Fig. 1.

Fig. 3 is a side elevational view showing 40 a modification in construction of the skee runner.

Fig. 4 is a fragmentary longitudinal sectional view taken on line 4—4 of Fig. 6, the parts being shown in an extended position and drawn to an enlarged scale.

Fig. 5 is a similar view of the same showing 45 the parts in a folded position, and

Fig. 6 is a longitudinal sectional view, the section being taken on line 6—6 of Fig. 4 showing the parts in an extended position.

Referring to the drawings, the numeral 10 indicates a conventional type of shoe or foot covering adapted to be worn by individuals and resting upon a plate 11, shaped in conformity with the shoe and having secured 55 at its outermost or heel portion a socket 12

adapted to receive the rear portion of the shoe, the socket having extending straps 14 capable of being secured together holding the shoe firmly, other straps 15 extending 60 upward from the sides of the plate 11, provided with buckles or similar fastening means engageable over the instep or front part of the shoe 10.

The front portion of the plate 11 is 65 formed to receive a pin 18, also passing through lugs 19, formed with the plate 20, the parts operating in the manner of a hinge, permitting the plates 11 and 20 to move upon the axis 18.

The plate 20 is firmly secured upon the upper surface of a pair of runners 21, integrally joined together at their upturned front portion 22, the rearwardly extending portions of the runners having secured upon 70 them a plate 23 adapted to receive the thrust of the socket 12 containing the heel of the operator, the side elements of the skee being further secured together by transverse bars 24, fixed upon their top edges and extended between the skee runner sides are lattice elements 25 adapted to make contact 75 with the snow surface.

The foregoing construction is such as to 80 permit the operator's feet to be raised in a manner similar to walking, thereby making the operation of the skee far easier than if the foot was rigidly engaged with the runners.

In the modification shown in Figs. 3 to 6 85 inclusive, a similar construction is used in securing the feet to the skee runner, which, in this case, is comprised of a pair of front elements 30 rigidly united at their curved and raised upper ends 31 and engaged with 90 rear elements 32 at a point immediately rearward of the heel of the operator, the rear elements being connected by transverse bars 33, similar to the bars 24.

The front and rear elements, respectively 100 30 and 32, are joined by a hinge of novel design, the same comprising a metal plate 35, pivotally secured to the adjacent ends of the elements 30 and 32, by pivot screws 36, having body portions 37 and extending heads 38, 105 while set in the outer sides of the elements 30 and 32 are other metal plates 40 secured by rivets 41 and containing lateral recesses 42, these recesses being receptive of key elements 44, having beveled lower ends 45 upon 110 one edge, while upon the other edge are extending lugs 46, the inner surface of the

lugs being adapted to make contact with the edges of the recesses 42.

The backs of the keys or bars 44 are adapted to make intimate contact with the beveled edges 48 of the plate 35, when the runners of the skee are extended at length as shown in Figs. 3 and 4 and with the corresponding surface 49, formed upon the lower or side edges of plate 35 when the 10 runner elements are in a folded position as shown in Fig. 5.

These keys have an extending operative head 50 and in order to hold these keys in proper operative position, and prevent their loss, a pair of plates 52 are secured upon the upper surface of the runner elements 30 and 32, the plate having openings through which the keys pass.

Formed with the plates 52 are inwardly 20 extending lugs 53, adapted to make contact with the lugs 46 when the keys are in a raised position preventing them from being removed from the space 42, similar lugs 54 being formed upon the inner sides of the 25 plate 52 acting as guides for the keys as they are raised or lowered.

In operation, when it is desired to fold the runners 30 and 32, of the skees, the keys 44 are raised by their handles 50, and drawn as 30 far out as they will go, permitting the elements 30 and 32 to fold upon the pivots 37, whereupon the keys are pressed inwardly coming against the surfaces 49, which hold the runners in a folded position as shown in 35 Fig. 5, and similarly, when it is desired to extend the runners, the keys are again raised and the runner elements extended horizontally, the keys are then pressed into position

acting in the manner of wedge levers, whereby the parts are held extended in a firm and 40 rigid manner.

From the foregoing it will be seen that a practical and effective joint has been presented which may be safely used by a person operating the skees, the parts being when extended substantially as rigid as if they were integrally formed, and it will be manifest that in carrying the skees the joint becomes of unquestionable use as the parts are permitted to be folded closely upon themselves. 50

Having thus described my invention what I claim as new and desire to secure by Letters Patent is—

1. A skee runner comprising front and rear sections, a block pivotally engaged with each of said sections, sliding keys adapted to be engaged with said block at the end of said sections when in an adjusted position, said keys operating to hold said skee runner sections rigidly when in either of their two adjusted positions, and means for preventing the removal of said keys. 55

2. A skee runner of the character described comprising front and rear sections, a block pivotally engaged with each of said sections, 65 sliding keys adapted to be engaged with said block at the end of said sections when in adjusted position, said keys operating to hold said skee runner sections rigidly when in either of their two adjusted positions, extending operating heads on said keys, and plates having openings through which said keys pass secured to said runner sections. 70

In testimony whereof I have affixed my signature.

STEPHEN WINTER.
